UNITED STATES PATENT OFFICE.

GUS A. BAHN, OF AUSTIN, TEXAS.

NAPKIN RING AND HOLDER.

SPECIFICATION forming part of Letters Patent No. 293,396, dated February 12, 1884.

Application filed December 13, 1883. (No model.)

To all whom it may concern:

Be it known that I, GUS A. BAHN, a citizen of the United States, residing at Austin, in the county of Travis and State of Texas, have 5 invented a new and useful Improvement in a Combined Napkin Ring and Holder; and I do hereby declare that the following is a full, clear, and exact description of the same, reference being had to the accompanying drawings, forming part of this specification, in which—

Figure 1 is a perspective view of the invention disposed as a napkin-ring; and Fig. 2 is 15 a view of the device, showing it applied as a napkin-holder.

My invention is in the nature of a combined napkin ring and holder, designed to receive the napkin after it is folded, or to be used as a device for sustaining the napkin at the neck 20 of the user when at the table. It consists in a yoke-shaped piece of metal having a hinged section for connecting the two ends, and serving as a ring, in combination with a clasp for holding the napkin, when used for holding the 25 napkin at the throat.

In the drawings, B represents a bowed or yoke-shaped strip of metal, and A is a section or strip of corresponding transverse dimension, hinged at a to one of the ends of the piece

B, and connected to the other end of said piece 30 B by a spring-catch, b. When said ends are connected by the section A, the device forms a closed band or ring, into which the napkin is inserted in the usual way. Upon the outside of one of the sides of the yoke B is attached a sliding clasp, C, fastened thereto by 35 a slot and a headed stud, c, passing through said slot. Now, to use the device as a napkin-holder, the section A is opened on its hinge, and the bowed or curved portion B is hooked 40 into the collar or wearing-apparel at the neck, as shown in Fig. 2, with the clasp C on the outside and the napkin caught between the latter and the section B. After the meal is over, the napkin-holder is detached, the section 45 A is closed, and the napkin is folded and passed through the device as a ring.

Having thus described my invention, what I claim as new is—

A combined napkin ring and holder, consisting of the two sections A and B, hinged together, and provided with a catch for fastening them, and a sliding clasp-piece, C, substantially as and for the purpose described. 50

GUS A. BAHN.
